UNITED STATES PATENT OFFICE.

JOHN G. BLESSING, OF CHICAGO, ILLINOIS, ASSIGNOR TO AUTOMATIC ELECTRIC COMPANY, OF CHICAGO, ILLINOIS, A CORPORATION OF ILLINOIS.

TRUNK-SELECTING SWITCH.

1,312,514.

Specification of Letters Patent.

Patented Aug. 12, 1919.

Application filed January 17, 1912, Serial No. 671,696. Renewed May 28, 1917. Serial No. 171,583.

To all whom it may concern:

Be it known that I, JOHN G. BLESSING, a citizen of the United States of America, and resident of Chicago, Cook county, Illinois, have invented a certain new and useful Improvement in Trunk-Selecting Switches, of which the following is a specification.

My invention relates to automatic or semi-automatic telephone systems, and it relates more specifically to an improved construction of a non-numerical trunk-selecting switch for use in such systems.

My invention relates to a trunk-selecting switch or rotary line switch of the type in which the wipers never release and rotate backward to normal, but have motion in a forward direction only. Heretofore, in switches of this type, the wipers of the line switch when idle remained in contact with the terminal of the trunk line which was last seized by the switch. In my improved construction, however, although the wipers of the switch never release back to normal position, they do not stand on bank contacts when idle. The bank contacts are separated by spacers wide enough to allow the wipers to rest between the adjacent contacts without touching the same. When a connection is released, the wipers simply move one step forward, off the contacts with which they were in engagement, but not onto the next contacts. The next time the switch operates, the wipers make one more step onto this next set of contacts, and if these contacts are busy the wipers are rotated automatically until an idle trunk is found.

Switches of this type have the advantage that their wipers do not return to normal after each call, and are thus not likely to have to rotate over busy trunks when a call is initiated.

A further advantage of my improved form of switch is the fact that the wipers do not normally stand on bank contacts, which makes it possible to simplify the construction of this type of switch. Heretofore, in line switches of this type, the wipers rested upon bank contacts all the time. It was therefore necessary to provide means for disconnecting the line relay from the line, and connecting the line with the wipers when the line to which the switch belonged became a calling line, and to also provide means for disconnecting the line relay but not connect the line with the wipers when the line became

a called line. This differential operation, which was necessary in prior switches of this type, is unnecessary in my improved construction for the reason that since the wipers do not rest upon the contacts normally, it does no harm to connect the line with the wipers, and thus the cut-off relay can operate in the same manner whether the line is being called or is calling.

These and other objects and features in my invention will be more readily and clearly understood by reference to the accompanying drawings, in which—

Figure 1 is a plan view of my improved rotary switch.

Fig. 2 is a sectional view taken on the line 2—2 in Fig. 1 to show the construction of the wipers and banks.

Figs. 3 and 4 show a complete connection between a calling substation A and a called substation A' in a system embodying the principles of my invention.

As shown in Fig. 1, the subscriber's individual switch comprises, among other details, a bank of contacts 2 and two sets of wipers 3, 4, 5 and 6 and 3^a, 4^a, 5^a and 6^a and for wiping over and making contact therewith. Corresponding wipers of each set are electrically connected together, and the two sets are so arranged that as one passes off the last contact of the bank the other passes onto the first contact. The bank 2 comprises four circular rows of contacts secured between suitable clamping plates and are suitably insulated from said plates and from each other. The wipers 3, 4, 5 and 6 and 3^a, 4^a, 5^a and 6^a are insulated from each other and fastened together and are secured to a toothed wheel 7 which is loosely mounted upon a pin 8 secured to the base plate 9. The pin 8 is located at the center of curvature of the bank 2, so that as the wheel 7 is rotated the wipers make successive contact with their respective contacts in the bank. Electrical connections are made with the wipers 3, 4, 5 and 6 and 3^a, 4^a, 5^a and 6^a through the medium of stationary brushes 10, 11, 12 and 13, which brushes bear against the central portion of the wipers. The means for rotating the wipers over the bank contacts comprises the electromagnet 14 and the lever comprising the two arms 15 and 16 which is secured to the armature of the magnet and loosely mounted upon the pin 23. The arms 15 and 16 co-operate with the

beveled teeth of the wheel 7 in such a manner that the wheel is rotated a distance equal to half the pitch of the teeth each time the magnet is energized or deenergized. The 5 contacts in the bank 2 are spaced apart so that when the magnet 14 it deenergized the wipers may rest between adjacent contacts without touching them. When the magnet is energized, the wipers are rotated onto the 10 set of contacts before which they were standing when the magnet was deenergized. The magnet 14 is provided with means for interrupting its own circuit, said means comprising the spring 17 and the contact screw 18. 15 Just before the armature of the magnet reaches its fully attracted position, the bushing 19 forces the spring 17 out of engagement with the screw 18 and bows it out so that it remains out of contact with the screw 20 until the armature is restored far enough for the bushing 20 to force it back to its original position. The power for restoring the armature of the magnet is furnished by 25 a spring 150. The circuits of the switch are controlled by the relays 21 and 22. These circuits are represented at C in Fig. 3. As shown in this circuit, the wipers 3 and 4 are the line wipers and the wiper 5 is the private or testing wiper. The relay 21 is the line 30 relay and the relay 22 is the cut-off or line-switching relay. One terminal of the relay 21 is connected to the battery lead 75, while the other terminal is connected to the line 64 through the normally closed contacts 69 35 and 70 controlled by the cut-off relay 22. The cut-off relay 22 is connected to battery in series with the magnet 14, the opposite terminal of this cut-off relay being connected to its own spring 72. The private 40 wiper 5 is connected to the contact 79 controlled by the relay 21, while the contact 68 is connected to a point midway between the relay 22 and the magnet 14.

The telephone system represented in Figs. 45 3 and 4 is the well-known type of automatic telephone system embodying subscribers' individual or preselector switches, so-called first selectors, second selectors and connectors. In this system each subscriber's line is 50 provided at the central office with an individual switch C of the type shown in Fig. 1. Corresponding contacts in the bank of a plurality of these switches are multiplied together and connected to trunk lines leading 55 to first selectors E. In this manner a small number of first selectors are made accessible in common to a plurality or group of subscribers. A number of first selectors in turn have common access to a plurality of trunk 60 lines leading to second selectors F, which in turn have access to trunk lines leading to connector switches H through the medium of which the connections are finally completed with the subscriber's line. The automatic substations A and A' may be of any

suitable common battery type of substation which is provided with a calling device of the proper character for controlling the central office apparatus shown herein. The substation A comprises the usual receiver 25, 70 transmitter 26, ringer 27 and switch hook 28. The automatic calling device may be of the type shown in the British patent to S. G. S. Dicker No. 29,654 of 1910, but is herein represented diagrammatically by a pair of impulse springs 29 and 30 and a toothed impulse wheel 31. The impulse wheel 31 is assumed to be controlled by the calling subscriber through the medium of a dial (not shown) provided with finger holes. In order to call any digit with such a calling device, the subscriber inserts a finger in the hole of the dial corresponding to the digit to be called and rotates the dial until the finger strikes a suitable stop, whereupon the finger 85 is removed and the dial allowed to return to its normal position. During the forward movement of the dial a number of teeth, corresponding to the digit to be called, on the wheel 31 are rotated past the end of 90 the spring, out of engagement with the spring 29.

The selector E is of the general type of selector switches disclosed in United States Letters Patent No. 815,321, granted to Keith, 95 Erickson & Erickson March 13, 1906, the circuits being modified, however, as shown in British patent to T. G. Martin No. 1419 of 1910, in order to operate in a system in which the central office apparatus is controlled by the calling subscriber over the two sides of the line in series. 100

The second selector F is essentially the same as the first selector E.

The connector H is of the general type of 105 connector switches disclosed in United States Letters Patent No. 815,176, granted to Keith, Erickson & Erickson March 13, 1906, but, like the selectors, is modified to operate in a two-wire system. Like the selectors, the 110 connector is provided with a shaft (not shown) carrying the wipers 52, 53 and 54 and controlled by the vertical magnet 55 and the rotary magnet 56. The usual side switch is controlled by the private magnet 115 57 in the usual manner. At 58 there is shown a ringing relay which is provided for the purpose of connecting ringing current with the called line after the connection has been completed. The talking circuit through the 120 connector is divided into two sections inductively connected through the condensers 59 and 60.

The substation A' and the line switch C' are identical with the substation A and line 125 switch C, respectively. At R there is shown a ringing current generator and at M a busy signaling machine is represented. A battery B having one terminal grounded at G is shown for the purpose of providing cur- 130

rent for operating the switches and for talking purposes.

Having given a general description of the apparatus with which I have chosen to illustrate my invention, as the operation of this type of system is well known it is not thought necessary to further describe its operation, except in so far as it relates to my improved line switch. The removal of 5 the receiver at the substation A from the switch hook permits the springs 61 and 62 to come into contact, thereby bridging the talking circuit of the substation across the line conductors 63 and 64, whereby a circuit 10 is closed through the line relay 21 of the switch C. This circuit extends from ground G' through the springs 65 and 66, line 63, springs 61 and 62, 29 and 30, receiver 25, transmitter 26, line 64, springs 70 and 69 and relay 21 to the battery lead 75 15 and thence through the battery B to ground G. The relay 21, upon energizing, completes a circuit extending from ground G' through the springs 76, interrupter springs 25 17 and 18 and the operating magnet 14 to the battery lead 75. As has been explained, the wipers of the switch normally rest between two successive sets of contacts in the bank of the switch. When the above circuit 30 is closed through the magnet 14, said magnet energizes and rotates the wipers one step onto the contacts immediately in front of them. If the trunk line which is connected to this set of wipers is idle, the magnet 14 35 remains energized and the wipers remain resting upon this set of contacts. If the first trunk line engaged by the wipers is busy, however, the circuit of the magnet 14 is automatically interrupted at the springs 40 17 and 18 and the wipers are automatically rotated until they do reach the contacts of an idle trunk. The manner in which the wipers are brought to rest upon the contacts of an idle trunk is as follows: It will be 45 seen that when a first selector E is idle, the private bank contacts of the trunk line leading to said switch in the banks of the line switch are grounded through the springs 77 and 78 of the relay 49 in the selector. Thus, 50 when the wiper 5 engages the contact of an idle trunk, a circuit is closed from ground G' through the springs 78 and 77, wiper 5, springs 79 and 80 of the relay 21, springs 81 and 72, cut-off relay 22 and the magnet 14 55 to the battery lead 75. Since the magnet 14 is energized at the instant this circuit is closed by the wiper 5, said magnet remains operatively energized in series with the cut-off relay 22, regardless of the interruption 60 of its original circuit at the springs 17 and 18. The relay 22, which is included in the locking circuit of the magnet 14, is operatively energized and operates to disconnect the line relay 21 and ground G' from the 65 calling line and to extend the line connec-

tion to the first selector E, as represented by the heavy conductors in the drawings. The relay 22, upon energizing, also completes a locking circuit for itself and the relay 14 independent of the ground G³ at 70 the selector E. This circuit extends from ground G⁴ (which is permanently connected with all of the contacts which are engaged by the wiper 6) through the wiper 6, springs 73 and 72 and through the relay 22 and the 75 magnet 14 to the battery lead 75. When the line circuit is extended through to the selector E, its line relay 48 is energized over a circuit extending from ground G⁵ through the lower winding of said relay, side switch 80 wiper 42, line switch wiper 4, thence over the heavy conductors to and through the substation A and back over the other side of the line, through the line switch wiper 3 and the side switch wiper 41 and the upper 85 winding of the relay 48 to the battery lead 78. The relay 48, upon energizing, completes an energizing circuit through the slow acting relay 49. The relay 49, upon energizing, separates the springs 77 and 78 to 90 disconnect ground G³ from the line switch private bank contacts of the seized trunk, so as to prevent another line switch from obtaining connection with the selector E while it is in use. The line relay 21, of course, 95 deenergizes when it is disconnected from the line by the operation of the relay 22, whereupon the wiper 5 is connected to a point between the relay 22 and the magnet 14 through the springs 79 and 82 and the 100 springs 68. The line relay 21 of the line switch C is preferably slightly slow acting, so that it will be certain not to complete the connection of the wiper 5 with the point between the relay 22 and the magnet 14 until 105 after the relay 49 at the selector has had sufficient time to energize and thus disconnect ground G³ from said wiper. As soon as the line switch C has completed connection with an idle selector E, the connector 110 private bank contacts of the calling line are provided with a guarding ground potential which extends from ground G⁴ through the wiper 6, springs 73 and 72 and the conductor 83 to said contacts. This guarding 115 potential protects the calling line from being called while it is in use.

Connection having been extended to an idle first selector by the removal of the receiver at the calling substation, the calling 120 subscriber now operates his calling device in accordance with the various digits of the number of the called line, so as to extend a connection to the called line in the manner well understood in the art. When connection is completed with the called line, the circuit of the cut-off relay 115 of its line switch C' is closed. This circuit extends from ground G¹¹ in the connector through the side switch wiper 114, springs 116 and 130

117, wiper 54, relay 115 and magnet 118 to the battery lead 75. The windings and resistances of the cut-off relays and motor magnets of the subscribers' individual switches are so proportioned that the current which flows through the motor magnet in series with the cut-off relay is not sufficient to operate the motor magnet, but is sufficient to maintain the motor magnet in its operated position if it is in that position when the circuit through the cut-off relay is closed. The only result of the closure of the above circuit through the relay 115 and the magnet 118, therefore, is to operate the relay 115. The relay 115, upon energizing, disconnects the line relay 120 from the line. The relay 115, upon energizing, also connects the called line with the wipers 121 and 122, but since the magnet 118 is not energized, these wipers are not standing upon any contacts, and the connection of the line therewith is, therefore, without any effect whatever.

Upon the completion of the conversation the entire connection is automatically released upon the hanging up of the receiver at the substation. During the time conversation is being carried on, the circuits of the release magnets of the switches E, F and H are maintained open by the relays 49, 91 and 101, which are energized over a circuit extending from ground G^s at the connector H through the spring 151 and its front contact, whence it branches, one branch passing through the relay 101, while the other branch extends through the side switch wiper 102, springs 103 and conductor 99 and thence to and through the relays 91 and 49 of the switches F and E. The hanging up of the receiver at the substation A separates the springs 62 and 61, thereby breaking the energizing circuit of the connector line relay 100. The relay 100, upon deenergizing, breaks the circuits of the relays 101, 91 and 49. These relays, upon deenergizing, complete the circuits of their respective release magnets 131, 133 and 46, which in turn, upon energizing, release their respective switches. The circuits of the release magnets are opened at the off-normal springs by the switch shafts when they reach their lowest position in a well-known manner. The connector switch, upon releasing, also destroys the energizing circuit for the cut-off relay 115 of the switch C', which relay, upon deenergizing, restores the individual switch of the called line to normal condition. The relay 49 of the selector E, upon deenergizing, also extends a connection from ground G^s through the springs 78 and 77, private wiper 5 of the switch C, springs 79 and 82 and the springs 68 to a point between the relay 22 and the magnet 14. The connection of ground G^s with this point short-circuits the relay 22, which thereupon de-

energizes. The springs of the relay 22 should be so adjusted that as the relay deenergizes the springs 72 and 73 separate to disconnect ground G^s from the circuit of the relay 22 and the magnet 14 an instant before the springs 68 separate to disconnect ground G^s . Therefore, when ground G^s is finally disconnected, there is no longer any circuit through the relay 22 and the magnet 14, and said relay and magnet finally de-energize. The magnet 14, upon deenergizing, permits the wipers of the switch to move one step off the contacts of the trunk line with which it had made connection and come to rest between said contacts and the next succeeding set.

While I have illustrated my invention in connection with one particular type of automatic telephone system, it will be readily understood that my improved line switch can be used in connection with any desired form of telephone system, whether automatic or semi-automatic. Likewise, it is not necessary that this line switch be used individual to a subscriber's line, as this same switch might be employed in any other position in the system. Many other modifications and changes which come within the scope of my invention will likewise suggest themselves to those skilled in the art.

What I claim as my invention is:

1. In a telephone system, a line, a trunk-selecting switch individual to the line comprising a series of contacts, a contact arm adapted to engage with said contacts, and means for normally maintaining said arm in a position between any two adjacent contacts.
2. In a telephone system, a line, a trunk-selecting rotary switch individual to the line comprising a series of contacts, a contact arm adapted to rotate over said contacts, and means for maintaining said contact arm in a position between any two adjacent contacts when said switch is idle.
3. In a telephone system, a non-numerical trunk-selecting switch, said switch comprising a series of contacts, trunks connected with said contacts, a contact arm adapted to be rotated over said contacts to select an idle trunk, and means for maintaining said arm between any two adjacent contacts when said switch is idle.
4. In a telephone system, a non-numerical trunk-selecting switch, a series of contacts, trunk lines connected with said contacts, a contact arm adapted to rotate in but one direction over said contacts to select an idle trunk, and means for maintaining said arm in a position between any two adjacent contacts when said switch is idle.

5. In a telephone system, a trunk-selecting switch comprising a series of contacts, a contact arm, a magnet for moving said arm step by step over said contacts, means for

- moving said arm onto one of said contacts when the magnet is energized, and means for moving said arm to a position between two adjacent contacts when said magnet is de-energized.
6. In a telephone system, a trunk-selecting switch comprising a series of contacts, a contact arm, means for rotating said arm over said contacts, said means including a ratchet and pawl mechanism, and a magnet for operating said mechanism to move said arm in contact with one of said contacts when said magnet is energized, and to move said arm to a position between two adjacent contacts when said magnet is deenergized.
7. In a telephone system, a subscriber's line, a non-numerical trunk-selecting switch for said line, said switch comprising a series of contacts, an arm adapted to be rotated in but one direction over said contacts, means for normally maintaining said arm in a position between two adjacent contacts, a magnet for operating said arm, means for energizing said magnet from said subscriber's line to move said arm onto one of said contacts, and means for automatically de-energized and again energizing the said magnet to move said arm to the next of said contacts provided said first-mentioned contact is busy.
8. In a telephone system, a non-numerical trunk-selecting switch including a line relay, a cut-off relay, an operating magnet, means for energizing said cut-off relay and magnet in series during the time a connection is maintained, and means for short-circuiting said cut-off relay when said connection is released.
9. In a telephone system, a plurality of trunk lines, a non-numerical trunk-selecting switch for selecting an idle trunk for extending a connection to a second automatic switch, an operating magnet and a cut-off relay for said trunk-selecting switch, means for energizing said magnet and cut-off relay in series when a connection is maintained, and means for short-circuiting said cut-off relay by establishing a ground connection at said second automatic switch when a connection is released.
10. In a telephone system, a plurality of trunk lines, a non-numerical trunk-selecting switch for selecting an idle trunk to extend a connection to a second automatic switch, said trunk-selecting switch including a pair of line wipers and a third wiper, a cut-off relay, an operating magnet, means for energizing said magnet and relay in series when a connection with said second switch is maintained through said line and third wipers, a connection from said third wiper to a point intermediate of said magnet and cut-off relay, and means for establishing a ground connection at said second automatic switch over said third wiper when said switch releases to thereby short-circuit said cut-off relay.
11. In a telephone system, a plurality of trunk lines, a trunk-selecting switch for selecting an idle trunk for extending a connection to a second automatic switch, said switch comprising a plurality of line wipers and a third wiper, a cut-off relay for said trunk-selecting switch, means for energizing said relay to extend a connection to said wipers, a locking circuit for said relay, and means for establishing a ground connection at said second automatic switch over said third wiper to short-circuit said cut-off relay when said second automatic switch releases.
12. In a telephone system, a plurality of trunk lines, a trunk-selecting switch for selecting an idle trunk for extending a connection to a second automatic switch, said trunk-selecting switch comprising a plurality of line wipers and a third wiper, a cut-off relay for said trunk-selecting switch, means for energizing said relay to extend a connection to said wipers, a locking circuit for said relay, an operating magnet connected in series with said relay when a connection with said second automatic switch is maintained, and means for establishing a ground connection at said second automatic switch over said third wiper to short-circuit said cut-off relay when said second automatic switch releases.
13. In a telephone system, a plurality of trunk lines, a trunk-selecting switch for selecting an idle trunk for extending a connection to a second automatic switch, said trunk-selecting switch comprising a plurality of line wipers and a third wiper, a cut-off relay for said trunk-selecting switch, means for energizing said relay to extend a connection to said wipers, a locking circuit for said relay, means for establishing a ground connection at said second automatic switch over said third wiper to short-circuit said cut-off relay when said second automatic switch releases, and means operated upon the deenergization of said cut-off relay for opening said locking circuit and disconnecting said third wiper from the circuit.
14. In a telephone system, a plurality of trunk lines, a trunk-selecting switch for selecting an idle trunk for extending a connection to a second automatic switch, said trunk-selecting switch comprising a plurality of line wipers and a third wiper, a cut-off relay for said trunk-selecting switch, means for energizing said relay to extend a connection to said wipers, a locking circuit for said relay, an operating magnet connected in series with said relay when a connection with said second automatic switch is maintained, means for establishing a ground connection at said second automatic switch over said third wiper to short-circuit said cut-off relay when said second automatic

- switch releases, and means operated upon the deenergization of said cut-off relay for opening said locking circuit and disconnecting said third wiper from the circuit.
- 5 15. In a telephone system, an operating magnet, a cut-off relay, a circuit for energizing said magnet and relay in series, said circuit including a pair of contact springs controlled by said cut-off relay.
- 10 16. In a telephone system, an operating magnet, a cut-off relay, a circuit for energizing said magnet and relay in series, said circuit including a pair of contact springs controlled by said cut-off relay, and means 15 for short-circuiting said relay to thereby deenergize both said relay and magnet.
17. In a telephone system, a switch comprising a series of contacts, a contact arm adapted to engage with said contacts, means 20 for normally maintaining said arm in a position between any two adjacent contacts, and a motor magnet for rotating said wipers one step upon energizing and another step upon deenergizing.
- 25 18. In a telephone system, a rotary switch comprising a series of contacts, a contact arm adapted to rotate over said contacts, means for maintaining said contact arm in a position between any two adjacent contacts 30 when said switch is idle, and a motor magnet for rotating said wipers one step upon energizing and another step upon deenergizing.
19. In a telephone system, a non-numerical trunk-selecting switch, said switch comprising a series of contacts, trunks connected with said contacts, a contact arm adapted to be rotated over said contacts to select an idle trunk, means for maintaining said arm between any two adjacent contacts when said 35 switch is idle, and a motor magnet for rotating said wipers one step upon energizing and another step upon deenergizing.
- 40 20. In a telephone system, a non-numerical trunk-selecting switch, a series of contacts, 45 trunk lines connected with said contacts, a contact arm adapted to rotate in but one direction over said contacts to select an idle trunk, means for maintaining said arm in a position between any two adjacent contacts 50 when said switch is idle, and a motor magnet for rotating said wipers one step upon energizing and another step upon deenergizing.
- 55 21. In a telephone system, a line, a trunk, a switch in the trunk and a switch in the line for connecting the line with the trunk, a line relay, a switching relay and a motor magnet in the line switch, an energizing circuit for the motor magnet and the switching relay controlled by the line relay and 60 the switching relay.
- 65 22. In a telephone system, a pair of lines, means for establishing a talking circuit between said lines, said means including any one of a plurality of trunk lines, a switch having a progressively movable wiper in- 70 cluded in the talking circuit, said switch having access to said trunk lines through said wiper, release means for said switch responsive to the opening of the talking circuit, and a plurality of positions in any one of which the said wiper may be held while the switch is released, said switch controlled over the two sides of the talking circuit in series.
- 75 23. In a telephone system, a pair of lines, means for establishing a talking circuit between said lines, said means including any one of a plurality of trunk lines, and a switch having a progressively movable wiper included in the talking circuit, said switch 80 having access to said trunk lines through said wiper, release means for said switch responsive to the opening of the talking circuit, and a plurality of positions in any one of which the said wiper may be held while the switch is released, one such position for each trunk line, said switch controlled over the two sides of the talking circuit in series.
- 85 24. In a telephone system, a pair of subscribers' lines, a pair of talking conductors individual to each of said lines, a switch controlled over said conductors in series for establishing a talking circuit between said lines, a contact arm for said switch, a group of trunk lines accessible to said switch 90 through said arm, a magnet controlled by opening said conductors for releasing said switch, and a position individual to each of said trunk lines in which said arm stands after said switch is released from the trunk 95 line last used.
- 100 25. In a telephone system, a pair of subscribers' lines, a pair of talking conductors individual to each of said lines, a switch controlled over said conductors in series for establishing a talking circuit between said lines, a contact arm for said switch, a group of trunk lines accessible to said switch through said arm, a magnet controlled by opening said conductors for releasing said switch, and a position individual to each of said trunk lines in which said arm stands after said switch is released from the trunk 105 last used, said arm remaining in said position until said switch is again brought into 110 use.
- 115 26. In a telephone system, a pair of subscribers' lines, a pair of talking conductors individual to each of said lines, a switch controlled over said conductors in series for establishing a talking circuit between said lines, a contact arm for said switch, a group of trunk lines accessible to said switch through said arm, a magnet controlled by opening said conductors for releasing said switch from any one of said trunk lines, a position individual to each of said trunk lines, means for holding said arm in any one of said positions after said switch is released, and means for advancing said arm 120 125 130

from the last released position when the switch is used for another call.

27. In a telephone system, a pair of subscribers' lines, a pair of talking conductors individual to each of said lines, a switch controlled over said conductors in series for establishing a talking circuit between said lines, a contact arm for said switch, a group of trunk lines accessible to said switch through said arm, means including a magnet controlled by opening said conductors for releasing said switch from any one of said trunk lines, a position individual to
- each of said trunk lines, and means for holding said switch in any one of said positions after said switch is released, said last mentioned means also for advancing said arm from the last released position when the switch is used for another call. 15

Signed by me at Chicago, Cook county, 20 Illinois, this 2nd day of January, 1912.

JOHN G. BLESSING.
